F. A. SAMPSON, JR

TRAY OR SINK LEG

Filed Aug. 23, 1921

Inventor
F. A. Sampson, Jr.

By
A. Randolph, Jr.
Attorney

UNITED STATES PATENT OFFICE.

FRANK A. SAMPSON, JR., OF KINGSTON, MASSACHUSETTS.

TRAY OR SINK LEG.

Application filed August 23, 1921. Serial No. 494,739.

To all whom it may concern:

Be it known that I, FRANK A. SAMPSON, Jr., a citizen of the United States, residing at Kingston, in the county of Plymouth and 5 State of Massachusetts, have invented certain new and useful Improvements in a Tray or Sink Leg; and I do hereby declare the following to be a full, clear, and exact description of the invention, such as will 10 enable others skilled in the art to which it appertains to make and use the same.

The invention relates to fixtures for supporting trays, sinks and like parts whereby provision is had for adjustment without requiring drilling and tapping of parts. 15

Other objects and advantages will be apparent and suggest themselves as the nature of the invention is understood.

While the drawing illustrates an embodiment of the invention it is to be understood that in adapting the same to meet different conditions and requirements, various changes in the form, proportion and minor details of construction may be resorted to without departing from the nature of the invention. 25

Referring to the accompanying drawing forming a part of the specification,

Figure 1 is a view in elevation of a support illustrative of the invention; a tray or 30 like part being indicated by the dotted lines.

Figure 2 is a sectional detail on a larger scale, parts being broken away, and

Figure 3 is a top plan view.

Corresponding and like parts are referred 35 to in the following description and designated in the several views of the drawing by like reference characters.

The support comprises a leg 1 and a horizontal strut 2, these parts preferably consist 40 of lengths of pipe which are threaded at opposite ends. A floor plate 3 is applied to the leg 1 and constitutes a foot therefor. A head or rest 4 is located at the juncture of the leg 1 and strut 2 and is apertured to receive such parts. The head or rest 4 consists 45 of a hollow casting which is constricted at its lower end and expanded at its upper end to receive the part to be supported such as a tray, sink or the like, a lip 5 extends vertically from the front wall of the head or rest 4 to engage the front of the tray, sink or like part and prevent forward displacement thereof. The upper threaded end of the leg 1 enters the lower end of the 50 head or rest 4 and receives a nut 7 which engages the lower end of the part 4 whereby

the same may be adjusted vertically as required. A nut 8 is located within the head or rest 4 adjacent the rear wall thereof and is prevented from forward displacement by 60 means of ribs 9 projecting inwardly from the side walls of the head 4. In this manner the nut 8 is held against the rear wall of the part 4 and receives the forward threaded end of the strut 2. 65

A plate 10 secured to the wall 11 is formed with a forwardly extending socket 12 and a lug 13. The nut 14 is seated in the socket 12 and receives the rear threaded end of the strut 2. The tray or part 6 rests 70 upon the lug 13. The socket 12 is closed by the wall 11 when the plate 10 is in position, thereby preventing displacement of the nut 14.

It will be understood from the foregoing 75 that the upper forward portion of the support is adjustable both vertically and horizontally. The vertical adjustment is primarily effected by means of the nut 7 which is threaded on the upper portion of the leg 80 1 and engages the lower end of the part 4 which loosely receives the upper portion of the leg. Horizontal adjustment of the support is effected by turning the strut 2 whereby the part 4 may be moved in or out so as 85 to clamp the part 6 between the wall 11 and the lip 5. The support provides for ready insulation of a tray, sink or like part and also provides for subsequent adjustment to compensate for coupling or other movement 90 rendering adjustment desirable and advantageous.

Having thus described the invention, what I claim is:—

1. A support of the class described comprising a leg, a head from which said leg depends, said head being upwardly enlarged and hollow, the upper edge of said head constituting an article supporting surface, a lip on said head extending above said surface for engagement with the article, a nut completely within the head, means integral with the head to hold said nut against rotation, a strut disposed at substantially a right angle to the leg passing into the head 95 and threaded to the nut, said nut also serving to space said strut below the said article-supporting surface to facilitate adjustment of the strut, and means adjustably supporting the strut at a distance from said 100 head.

2. A support of the class described com-

prising a leg, a head into which the upper end of said leg extends, a nut threaded on said leg and constituting a support for the lower edge of said head, said head being upwardly enlarged and hollow, the upper edge of said head constituting an article supporting surface, said head having a lip integral therewith extending above said surface for engagement with the article, ribs 10 integral with the head and extending into the hollow thereof, a nut completely within the head held against rotation by said ribs, a strut disposed at substantially a right angle to the leg passing into the head and threaded to the second mentioned nut, said second mentioned nut also serving to space said strut below the said article-supporting surface to facilitate adjustment of the strut, and means adjustably supporting the strut at a distance from said head. 20

In testimony whereof I affix my signature in presence of two witnesses.

FRANK A. SAMPSON, JR.
